ABSTRACT OF THE DISCLOSURE

An improved form of particle classifying-separating-collecting apparatus, more particularly an adjustable partitioning means in a collector bin for effecting the collection of different classes of particles.

The present invention relates to an improved form of particle classifying-separating-collecting apparatus, and more particularly to an adjustable partitioning means in a collector bin for effecting the collection of different classes of particles.

In the operation of power plants equipped with coal burning stokers, or with certain other industrial operations, it is frequently desirable to separate and collect the solid particles which are being discharged or carried along with a gaseous stream. These particles can be classified by difference in size, difference in density, or difference due to the combination of these two basic characteristics. To avoid confusing the classes so obtained from classifications according to weight only, the term "inertia mass" will be used hereinafter to differentiate the characteristics of the classes of particles so obtained. Isolation of different classes of particles is desirable, for example, in burning solid fuels in suspension in air, the particles of fuel are or may be of unequal size. Consequently, the finer particles burn more quickly than the larger particles which may not burn completely and, therefore, retain a part of their fuel value. The particles or ashes remaining after combustion are generally classified by inertia mass, separated from the exhaust gases, and collected according to their inertia mass classification. The particles of larger inertia mass are recycled for further burning and the particles of smaller inertia mass are discarded. In the operation of power plants, however, different fuels are burned under different environmental conditions, thus the size of the particles which are of value for recycling may vary, but the ability to adjust the demarcation between classifications has not existed heretofore. Thus far, particles have been separated into only two classifications, without isolating other inertia mass classifications of particles. Furthermore, in the past, separate fixed dimension bins have been used for the collection of each classification. This practice has proved quite space consuming.

It is a principal object of my invention to provide an adjustable classifier-collector capable of multiple and varying classifications while realizing a reduction of space required. My invention can be used to separate for recycling partially burned particles of fuel, while removing completely burned particles for disposal. Another use is in separating particles used in catalytical processes for re-use, disposal, or further processing. Other uses include separation of absorbents by density for appropriate disposition, recovery and grading of particles used as abrasives, separation of mixtures of different types of particles, and separation of broken pieces from undamaged pellets in various industrial uses. The adjustable portion of the invention is readily adaptable to either manual or automatic control operated either proximately or

2

remotely. My invention can best be described as being, in a particle separator-classifier apparatus which differentially separates particles from a particle laden gas stream according to the inertia mass of the particles such that particles of different inertia masses are discharged from different zones thereof, the improved construction and arrangement which comprises a single bin below and in open communication with the entire particle discharge portion of the apparatus, said bin being provided with gate means pivoted in the lower portion and adjustably movable to in turn provide varying sized compartment and varying sized inlet passageways to such compartments within said bin, said bin narrowing at the lower portion where at least one particle outlet port is provided for each compartment, whereby the division of large and small inertia mass particles can be regulated to flow into said varying sized compartments of said bin and whereby the particles may be withdrawn from the separate outlet ports from the respective compartments.

My invention provides a solution to the problem of an inflexible division between classifications through the use of a movable gate means which divides a unitary collector bin into separate compartments. Also, the limitation to two classifications is overcome through the use of multiple gates. A substantial savings in space is accomplished through the use of a single collection bin divided into compartments.

In my invention, suspended particles are first caused to be classified according to their inertia mass in an initial inlet section or plenum. This is accomplished by passing a particle laden stream of gas through a lateral inlet to a horizontally disposed plenum chamber, where the inertia of the entrained particles will carry them a distance across the plenum chamber in proportion to their individual inertia masses. The particles then descend into and pass through spaced centrifugal separators where they are separated from the gas stream and discharged into a single collection bin, which is divided into at least two compartments. The compartments are positioned under the centrifugal separators in a manner transverse to the direction of flow of the laden stream so that the particles of largest inertia mass fall into the furthermost compartment with respect to the stream inlet, while the lightest particles of smallest inertia mass fall into the nearest compartment, and all other particles will fall into compartments in between, according to their relative inertia masses. The bin of the unit is provided with a movable partition or gate which can be adjusted from outside the compartments or bin by either manual or automatic means.

There is achieved then, in the use of a single bin with multiple compartments, an increase in the flexibility of selective collection plus a decrease in the space required for collection.

The various features of my invention are illustrated, by way of example, in the accompanying drawings in which:

FIGURE 1 is a vertical section of one embodiment of an apparatus for classification, separation and collection;

FIGURE 2 is a partial vertical section of another embodiment showing only the collection unit.

Referring to FIGURE 1, the classifier-separator comprises a lateral inlet 1 into a plenum chamber 2 which is defined by a lower horizontal tube sheet 4 and an upper sloping tube sheet 13, below which are spaced centrifugal separating tubes 3 mounted in said tube sheet 4. The tubes 3 discharge particles into a single bin 6 and exhaust gas passes through off-take pipes 5. The bin 6 is divided into compartments 7 for which the area can be varied by gate means 8, which is pivoted about shaft means 9 and is controlled by a motor or other power supply means 10 connecting with gear means 11.

In the operation of the unit, a particle laden gas stream enters the plenum chamber 2 through lateral gas inlet 1 causing the particles of largest inertia mass to be carried to the distant end of the chamber, while the particles of smallest inertia mass remain nearer the gas inlet 1. The particles then descend into centrifugal separator tubes 3, from which the gas is removed through off-take pipes 5 into the cleaned gas off-take section 14 and through a cleaned gas outlet passage 15. The particles then pass through the particle discharge portion 16 of the classifier-separator apparatus and into the collection bin 6 where the particles are directed into varying sized compartments 7 within the collection bin 6. The direction of particles is accomplished through the adjustment of a movable gate means 8 which is pivoted about a shaft means 9 and is operated by the electric motor 10 transmitting power through the gear train 11. The particles are drawn off from the compartments for disposition through respective outlets 17 of compartments 7.

Referring to FIGURE 2, there is shown a partial sectional view of a modified form of the invention. An upper section, not shown, may be similar to that shown in FIGURE 1, where a multiplicity of centrifugal separators will cause the separated particles to descend into the various compartments 7' of the single bin 6', the compartments being separated by gate means comprising gates 18 and 19. The collection of particles into particular compartments is accomplished through the adjustment of movable gate means 18 and 19, which are pivoted about the respective shaft means 20 and 21, and shown in this instance as being manually controlled by the respective lever means 22 and 23. The particles are drawn from the compartments for disposition through respective outlet 17' of compartments 7'.

I claim as my invention:

1. In a centrifugal separator type of particle separator-classifier apparatus which differentially separates particles from a particle laden gas stream according to the inertia mass of the particles such that particles of different inertia masses are discharged from different zones thereof, which apparatus is characterized by centrifugal separating means for separating particles from a particle laden gas, and particle collecting means below the centrifugal separating means for collecting particles discharged therefrom, the improved construction and arrangement which comprises a single bin below and in open communication with the entire particle discharge portion of the apparatus, said bin being provided with gate means pivoted in the lower portion and adjustably movable to in turn provide varying sized compartments and varying sized inlet passageways to such compartments within said bin, said bin narrowing at the lower portion where at least one particle outlet port is provided for each compartment, whereby the division of

large and small inertia mass particles can be regulated to flow into said varying sized compartments of said bin and whereby the particles may be withdrawn from the separate outlet parts from the respective compartments.

2. The apparatus of claim 1 further characterized in that individual gates of said gate means are rigidly joined to rotatable shaft means and the movement of the gate means is selectively controlled by lever means connected to the shaft means.

3. The apparatus of claim 1 further characterized in that individual gates of said gate means are rigidly joined to rotatable shaft means and the movement of the gate means is selectively controlled by power driven means transmitting power selectively to said shaft means.

4. Apparatus for classifying, separating, and collecting suspended particles from gases which comprises in combination, a lateral gas inlet into a plenum chamber, a cleaned gas off-take section, spaced centrifugal separator tubes depending from said plenum chamber and having open upper end portions to receive particle laden gases therefrom, said centrifugal separator tubes each having an off-take pipe extending upward therefrom to said gas off-take section, a single particle collection bin below said gas inlet plenum chamber and encompassing said separator tubes, a gate pivoted in the lower portion of said bin and adjustably movable to provide two varying sized compartments and the resulting varying sized inlet passageways to such compartments within said bin, said bin narrowing at the lower portion thereof with one particle outlet port being provided for each compartment, whereby in said apparatus the particle laden gas stream laterally entering said plenum chamber propels the particles of greater inertia mass to the far side of said plenum chamber while the particles of lesser inertia mass are propelled only to the near side of said plenum chamber, all particles then descending into centrifugal separator tubes from where they are directed into the appropriate compartment of said bin from where said particles pass through their respective outlet ports.
